UNITED STATES PATENT OFFICE.

ALBERT H. MCALLISTER, OF COTTON PLANT, MISSISSIPPI.

IMPROVEMENT IN SAFETY WHIFFLETREES.

Specification forming part of Letters Patent No. 122,394, dated January 2, 1872.

Specification describing a new and Improved Safety Whiffletree, invented by ALBERT H. MCALLISTER, of Cotton Plant, in the county of Tippah and State of Mississippi.

The object of this invention is to provide ready and convenient means for liberating a horse or horses from a carriage or other vehicle while the horse is in motion; and it consists in the construction of the trace-hooks and in two liberating levers attached to the whiffletree, and in the construction, arrangement, and combination of parts, as hereinafter more fully described.

In the accompanying drawing, Figure 1 represents a top view of a whiffletree provided with my detaching apparatus partly in section. Fig. 2 is a view, showing the back edge of the whiffletree and the manner in which the levers are made to engage with the trace-hooks. Fig. 3 is an enlarged view of one end, looking from the line *x x* of Fig. 1. Fig. 4 is a perspective view of the trace-hook with a portion of the trace.

Similar letters of reference indicate corresponding parts.

A is the whiffletree. *B B* are the cuff-irons on the ends thereof. These irons extend beyond the ends of the whiffletree, so that there are recesses to receive the trace-hooks, as seen in Fig. 1. *C* is the trace-hook. *D* is a bit, and *E* is a guide-pin on the end. The cuffs *B B* have each a plate, *F*, which is bent at right angles with the ends, as seen in Fig. 1. Through this plate is a hole for the pin *E*. *G G* are iron plates on the ends of the whiffletree, within the cuffs *B B*. *H H* represent the beveled corners of the whiffletree. *I I* are the two tripping-levers, whose fulcrums are at the points *J J*. *K K* are springs which bear against the short ends of the levers with a constant press-

ure. These levers extend to about the middle of the whiffletree, with a ring, *L*, each, to which is attached the liberating-cord *M*, as seen in the drawing. *N* is a guide-plate.

Now, if this cord be pulled in the direction indicated by the arrow in Fig. 2 the result will be that the bits of the trace-hooks, which are held by the concave ends of the tripping-levers *I I* on the plates *G G*, will be forced off those plates, which will liberate the traces from the whiffletree. The springs *K K* keep the levers *I I* in position, and securely confine the traces when everything is "all right;" but if anything breaks and the horse or horses become unruly, and danger is apprehended, all the driver has to do is to pull the cord and let the horse or team "go."

I do not confine myself to the particular form or arrangement of any of the parts described, as they may be varied in many ways without departing from my invention.

Having thus described my invention, I claim as new and desire to secure by Letters Patent—

1. In combination with a whiffletree, the tripping-levers *I I*, springs *K K*, and cord *M* and bit *D* of the trace-hook, substantially as and for the purposes described.
2. The bit *D*, in combination with a trace-hook, as and for the purposes described.
3. The guide-pin *E* on a trace-hook, as and for the purposes described.
4. The cuff-irons *B B*, in combination with the trace-hook *C* and whiffletree *A*, when said irons are constructed and arranged on said whiffletree, as shown and described.

A. H. MCALLISTER.
